UNITED STATES PATENT OFFICE.

SAMUEL J. HEILIGERS, OF FINDLAY, OHIO.

DISPLAY DEVICE FOR GARMENT MATERIALS.

1,183,876.

Specification of Letters Patent.

Patented May 23, 1916.

Application filed April 5, 1915. Serial No. 19,360.

To all whom it may concern:

Be it known that I, SAMUEL J. HEILIGERS, a citizen of the United States, and a resident of Findlay, in the county of Hancock and 5 State of Ohio, have invented certain new and useful Improvements in Display Devices for Garment Materials, of which the following is a specification.

My invention relates to devices for displaying garments or garment materials; and its object is to indicate the appearance of cloth or other garment material in connection with the style in which the material is made up in the garment.

15 My invention consists in the combination of parts and in the details of construction and arrangement of parts as will herein be more fully described and claimed.

In the drawings: Figure 1 is an enlarged 20 plan view of apparatus embodying my invention; Fig. 2 is a rear elevation of the same; Fig. 3 is a vertical section on the line $x-x$ of Fig. 2; Fig. 4 is a front elevation of the same, showing the display of one style 25 of garment; Fig. 5 is a similar view showing a display of another style of garment; and Fig. 6 is a side elevation of the apparatus, showing how it is opened for changing the cloth or other material displayed therein.

30 As I prefer to construct my invention, the frame 1 has suitable base members 2 for supporting it in upright position, which base members may have casters 3 for conveniently moving the apparatus.

35 My invention involves the use of a screen with a rift or aperture through which garment material may be seen, and which rift or aperture is given a configuration to represent the shape of the outline of garment on a 40 figure like that on which it is to be worn. This screen may consist of any extended surface of material, preferably opaque, and which surface may bear or include representations of other parts of the figure not covered by the garment as worn. As I prefer to provide this screen, a glass plate 5, is supported against a ledge 4 around the interior front edge of the frame 1; this glass plate being provided with a coating on its surface,

45 preferably the rear surface, and leaving the rift or aperture 6 of the proper shape in this

coating, through which rift or aperture 6 and through the transparent plate 5 the garment material may be seen, to produce the effect as above described.

55 The representations of the other parts of the figure, as above alluded to, preferably form part of the coating. Thus, this plate bears the representations 7 of the head and neck and neckwear of a human figure and 60 the representations 8 and 9 of the hands and shirt cuffs, as well as representations 10 and 11 of the feet and shoes of the figure; the aperture 6 being of such configuration that it will, with the cloth or the garment material displayed through it in conjunction 65 with the above representations, represent a complete human figure wearing garments made of said cloth or other garment material. Also, if desired, suitable background 70 figures, such as the chair 12 and desk 12' may be included to make the display attractive, as is usual in making up clothing display illustrations. This opaque screen, including these figures may best be placed 75 upon the glass by some transfer process, such as those which are well known and need not be particularly described herein.

The cloth or other garment material 13 is held up against the rear surface of the glass 80 or of the coating of the glass, to be displayed through the aperture 6, by means of a back 14 which has hinges 15 hinging it to the bottom of the frame 1, so that it may swing backward and downward. The back 85 preferably has a suitable prop 16 connected to it by means of a hinge 17 slightly above the middle of the back, which, when the back is swung backward and downward, as shown in Fig. 6, will swing outward and 90 backward and engage with the floor and properly support the back in opened position. When the back 14 is swung upward and forward into the frame to hold the material 13 in position, the prop will hang vertically close against the back as shown in 95 Figs. 1, 2 and 3.

100 Preferably, as shown, an extra cross piece 18 is provided in the upper part of the frame and permanently secured therein behind the plate 5, thus holding the plate in position at all times, and the back 14 is

made of length to have its upper end come close under this cross-piece 18 when closed, and a suitable button 19 is mounted on the cross piece 18 to engage down against the 5 back 14 and hold it up in closed position; this button being swung upward to either side to release the back for opening. The placing of this cross-piece 18 in the frame, as shown and above described, is permissible, 10 because the upper part of the plate 5 is occupied by the representation of the head and neck portions of the figure. Therefore the cross-piece does not encroach upon the rift or aperture 6 so as to be seen there- 15 through, and allows the piece of material 13 to extend past the upper end of the rift or aperture 6; this piece of material 13 being substantially conterminous with the back 14 at the upper end. It will also be 20 understood that the material 13 should extend below the lower end of the rift or aperture 6 and be of ample length to extend beyond both sides thereof. Also, the frame 1 and the plate 5 are made amply wide to 25 afford considerable background or marginal space at each side of the representation of the figure; and, it not being necessary that the contact of the cloth or other material 13 with the back of the plate 5 or the coating 30 thereof be of greater transverse extent than the greatest transverse extent of the rift or aperture 6, the back 14 may be made of considerably less width than the interior of the frame 1, as shown.

35 With the device constructed as so far described, there will not be a complete representation, since the details of the garment will not be shown. These details are provided by graphically or otherwise representing them in such a manner that they can be interposed between the garment material 13 and the plate 5 with its coating and the rift or aperture 6 therein, the details preferably being graphically represented upon a transparent piece of material. 40 They are made to conform to the configuration of the rift or aperture 6 in such a manner as to complete the representation of the garment in conjunction with the garment material showing through the aperture.

45 The above or any similar representation of the details of the garment may be provided for a single style of garment and left in position permanently. However, it is highly desirable to be able to conveniently change the representation of the details of the garment to indicate how the garment will appear as made in various styles from the particular piece of material being 50 played in the device; or, by substituting different pieces of material to be able to show various styles in conjunction with materials of various kinds and patterns.

Such change of the details may be effected

by substituting different pieces of transparent material to be interposed as above described with the details represented thereon, and by providing some means for holding such transparent piece in position so that its details conform with the configuration of the rift or aperture 6.

I provide for conveniently substituting different details in conjunction with a display of a single piece of garment material without removing the piece of garment material from the device, by making the transparent piece in flexible form, as of celluloid or other suitable flexible transparent material; or by otherwise combining the details in a single continuous film or web for bringing them successively into position for displaying them through the rift or aperture 6. Thus, as shown herein, a film or web 20, suitably constructed as above described, passes transversely between the material 13 and the back of the plate 5 with the coating thereon and the rift or aperture 6 therein, and is wound onto rollers 21 at opposite sides of the frame; these rollers 21 being journaled on vertical axes in upper 90 brackets 22 and lower brackets 22' fixed on the backs of the sides of the frame 1. In each upper bracket 22 is a horizontal shaft 23 with a gear 24 meshing with a gear 25 fixed to the respective roller 21, and each 95 shaft 23 has a crank 26 fixed thereon for turning it. By this means, the web 20 may be wound from either side to the other and bring the desired set of representations of the details which it bears into the proper 100 relation with the rift or aperture 6.

In many instances, the device need be provided for changing only the details of the coat; as it will not usually be necessary to provide a change of details of the 105 trousers in indicating the styles of suits. For such use, the web 20 need be made of vertical width only sufficient to carry the details of the longest coat displayed, as of the frock coat as shown in Fig. 5, and the 110 rollers 21 may be made of corresponding length and mounted accordingly. However, it will be understood that it may be necessary to represent practically the entire lengths of figures in indicating different 115 styles in trousers; or for indicating the styles of long coats such as overcoats, or, if the device is to be used for displaying ladies' garments, for indicating different 120 styles of skirts. For such use, the web 20 is made of the full height of the figure, as shown herein.

The termination of the back 14 laterally some distance inward from the corresponding sides of the frame 1, as before described, 125 leaves an ample open space for the passage of the film or web 20 over from the roller 21 to the inner side of the back 14 and ma-

terial 13 held thereby, so that the film or web 20 is not subjected to any sharp turns or abrasion with hard surfaces. The only turn that the web makes is over the corner 5 of the back 14 and the material 13 thereon; and here the web is protected by the material 13, which is usually of cloth of texture soft enough to avoid any injurious abrasion of the web or film 20.

10 In arranging the device for display of a certain material it is necessary only to cut off a convenient length of the material and place it upon the back 14 while the back is opened to such a position as shown in Fig. 15 6, and then close the back, bringing the material up into position. It is not necessary to open the back in order to change the display of garment style details, because the web or film 20 may be wound in 20 either direction between the material 13 and the back of the plate 5 and its coating. The web or film 20 will not be seriously abraded by the back of the plate 5 or its coating, since it is stretched back against 25 the garment material 13 throughout its extent where it comes between the material 13 and said plate 5 and its coating.

From the above it will be seen that it is possible to readily change the material to 30 be displayed, and also to change the display of garment style details, and each change may be changed without disturbing the other. At the same time the arrangement of the parts is such that none of these are 35 seriously worn or injured in manipulation.

The possibility of readily making both kinds of changes as above described makes my improved device not only suitable for more or less permanent window displays, 40 but also for displaying materials to customers in the store or tailoring shop. Any piece of goods that the customer may like may be shown in various styles to enable the customer to determine which style will 45 be selected; the desired piece of goods being placed in the device and the web or film 20 manipulated to show successively the various sets of details to represent this piece of goods made up in such various styles. 50 If the customer has decided upon the style to be selected, the film or web 20 may be left to display a single set of details; and various pieces of material may be successively placed in the device, enabling the cus- 55 tomer to select a suitable piece of goods which he thinks most appropriate in the style indicated.

Having fully described my invention, what I claim as new and desire to secure by 60 Letters Patent is:

1. In a device for displaying garment materials, in combination with a screen having a rift of garment-outline-representing formation, a plurality of different sets of

garment-detail representations each adapted 65 to be conformed to and within said rift to modify the display, said sets of representations being arranged successively in the form of a web, means for supporting and moving said web, in juxtaposition to said 70 screen, to bring said sets of representations successively into their conforming positions within said rift, and means for supporting the garment material to be seen through said rift in conjunction with said representations. 75

2. In a device for displaying garment materials, in combination with a screen having a rift of garment-outline-representing formation, a transparent web, different sets 80 of graphic representations of garment details on said web, means for supporting and moving said web in juxtaposition to said screen to successively display said sets of representations in said rift, and means for 85 supporting the garment material to be seen through said rift in conjunction with said representations.

3. In a device for displaying garment materials, a transparent plate having a coating 90 forming a screen thereon, said coating having a rift of garment-outline-representing formation, a frame, and means supporting said transparent plate in said frame, a flexible web comprising different sets of 95 garment-detail representations arranged successively thereon, rollers at opposite sides of said frame on which said web is wound for supporting and moving said web to bring successive ones of said sets of representations into juxtaposition with said plate and its screen-forming coating, whereby 100 said sets of representations in such positions conform to and are in said rift in said coating, to modify the display and a back mov- 105 ably mounted on said frame to hold garment material in position to be seen through said rift in conjunction with said representations, or to permit said material to be removed without moving said web, said back 110 being of materially less width than said plate and positioned substantially in the middle of said frame, whereby spaces are left at the sides of the frame, back of said plate, for the free passage of said web from 115 respective ones of said rollers at the sides of the frame to and between the garment material and the back of said transparent plate, whereby said web may be freely wound from one of said rollers to the other 120 to move said sets of representations successively into said juxtaposition without moving said back and garment material.

4. In a device for displaying garment materials, in combination, a glass plate and 125 a screen-forming coating on the back of said plate, said coating having a garment-outline-representing rift therein, a flexible

transparent web, different sets of graphic representations of garment details on said web, means for winding said web across and in juxtaposition with said plate and its coating to successively display said sets of representations in said rift, and means for supporting garment material against the back of said web to be seen through said web and

through said rift in said coating and through said glass plate in conjunction with 10 said representations.
